UNITED STATES PATENT OFFICE.

ORLANDO W. NORCROSS, OF WORCESTER, MASSACHUSETTS.

FLOORING FOR BUILDINGS.

SPECIFICATION forming part of Letters Patent No. 698,542, dated April 29, 1902.

Application filed November 22, 1901. Serial No. 83,278. (No model.)

To all whom it may concern:

Be it known that I, ORLANDO W. NORCROSS, a citizen of the United States, residing at Worcester, in the county of Worcester and State of Massachusetts, have invented a new and useful Flooring for Buildings, of which the following is a specification.

This invention relates to a flooring for buildings which has been designed with a view of securing the advantages, first, of entirely dispensing with all girders or floor-beams, which have heretofore been regarded as absolutely essential for supporting the floors of buildings; second, to provide a form of flooring which will utilize to best advantage the immense crushing strength of concrete, and, third, to provide a strong inexpensive solid inflexible flooring which can be laid in place by unskilled labor.

20 To these ends this invention consists of the flooring and the combinations of parts therewith, as hereinafter described, and more particularly pointed out in the claims at the end of this specification.

25 In the accompanying three sheets of drawings, Figure 1 is a perspective view, partially broken away, of a section of flooring supported and constructed according to my invention. Fig. 2 is a fragmentary plan view of a portion 30 of the metallic network of a floor constructed according to my invention. Fig. 3 is a detail view of two floors constructed according to my invention and posts for supporting the same. Fig. 4 is an enlarged fragmentary view 35 illustrating the disposition of the metallic network in a floor constructed according to my invention when it is desired to have a maximum amount of metal at the middle of a span between two posts and also illustrating a spring-prop which may be employed for supporting a floor constructed according to my invention after the stagings have been taken down, and Figs. 5 and 6 are detail views 40 of one of such spring-props.

45 One of the most serious problems in erecting all classes of buildings is the selection of a proper flooring. The defects of ordinary wooden floorings and the dangers from using the same have been almost universally recognized.

50 The disadvantages in the use of ordinary wooden floorings are not simply those arising

from the danger from fire, but on sanitary grounds alone nothing could possibly be more opposed to the principles which constitute a healthy dwelling than wooden floors of ordinary type, the inclosed tubes and passages of a wooden floor affording safe retreat in which rats, mice, cockroaches, and other vermin find perfect breeding-quarters, and in constructions where hollow bricks are employed for the ostensible purpose of admitting air for preventing dry rot from attacking the timbers the filthy condition of the floor-spaces creates positive danger to human health and existence. For these reasons wooden floors are now approved by the best authorities only for use in the more flimsy and temporary class of constructions. On the other hand, a substitute for ordinary wooden floorings has heretofore never been devised which is sufficiently cheap, durable, and easily handled to be adapted for ordinary dwelling constructions, while even in the larger and more costly buildings many of the flooring systems now employed are extremely defective.

55 In all classes of buildings, either those of a dwelling type or of the larger and more costly buildings, it has heretofore been thought necessary to either rest or hang the floors upon 60 girders or floor-beams.

65 In the larger types of buildings heavy rolled iron girders are now universally employed and associated with narrower floor-beams, each panel or section between the floor-beams constituting, in effect, a separate floor-section. The use of these heavy iron girders in building constructions is objectionable not only on account of the first cost of the material and 70 on account of the skilled labor required for 75 securing the same in place, but these beams themselves are necessarily frequently in the way, projecting down into the apartment below the same and being a constant source of 80 annoyance by reason of intersecting light and 85 occupying room. Furthermore, the main beams or girders of a building of this type necessarily have to be inclosed or cased in some suitable manner to protect them from 90 fire and to cover their unsightly appearance. 95

100 In a flooring constructed according to my invention I propose to entirely dispense with all floor-beams, girders, joists, or other horizontal supports, providing a construction in

which a flooring is directly supported upon separated posts. In accomplishing this purpose I have succeeded in providing a form of flooring which utilizes the immense crushing strength of concrete to the best possible advantage.

As herein illustrated, a flooring constructed according to my invention consists, essentially, of a panel of concrete having metallic network incased therein, so as to radiate from the posts on which the floor rests.

The metallic network of my flooring is formed by strips of suitable wire-netting. In practice I have used a hog wire fencing, which is a fencing of the same class as ordinary poultry wire fencing, except that the same is made of considerably heavier wire.

In laying a flooring constructed according to my present invention the posts are first erected, and a temporary staging is built up level with the tops of the posts. Strips of the wire-netting are then laid loosely in place on top of the staging. In practice I have laid this wire-netting in straight lines from post to post and also crossing diagonally from post to post. A number of layers of this wire-netting are preferably employed, said layers being laid together at their crossing-points in cob-house fashion, the number of such layers depending on the thickness of the flooring, the weights to be supported, and the distance separating the posts. The concrete is then spread upon or molded in place on the staging to inclose the metallic network. The character of the concrete employed can be varied according to the supply of material which can be conveniently procured and the requirements to which the flooring is to be submitted. In practice I have sometimes laid the concrete in layers of different quality, the lower layer of the flooring which incloses the wire being laid with the best quality of concrete available. The center concrete of the flooring may be laid with cinder concrete or concrete employing some light material as an aggregate, the upper surface of the flooring, if desired, being finished with a facing of neat Portland cement or the better grades of concrete. This I have found to be of advantage, because, although the cinder concrete is not of as great strength as a rock concrete, the lighter weight of the cinder concrete more than compensates for the difference in its strength when laid as the center layer of the flooring, which center layer of the floor being substantially at the neutral axis of the floor is not called upon to resist as heavy strains as the top or bottom layers of the flooring. After a flooring has been laid in this manner it is allowed to set or harden for as long a period as can conveniently be done without retarding the construction of the building. In many instances, however, it is desirable to take down the staging used in laying the flooring, so that the same may be moved out of the way or may be employed for laying the successive floorings above. To provide

means for permitting this to be done without endangering the safety of the floors already laid, I have provided for the use of spring-props, which are spaced or distributed between the posts and are driven tightly in place to assist in holding up the flooring until the time when the flooring shall have set or hardened with sufficient permanence to prevent any possible injury to the flooring. These spring-props are preferably permitted to remain in place for as long periods as possible, in practice these props being retained until the main construction-work of the building has been entirely completed and the building ready for finishing.

In finishing floorings constructed according to my invention an ordinary wooden flooring may be laid directly on the upper surface of the concrete or may be leveled and supported by thin furrings, while the plastering may be directly applied to the under surface of the concrete or wire lathing supported therefrom, as preferred.

In a completed flooring constructed according to my invention it will be seen that instead of resting or hanging a flooring in place upon beams or girders the flooring rests upon separated posts or other supports and consists of a single concrete panel having a wire network inclosed therein in proper position to support the tensile strains, the concrete itself on account of its well-known crushing strength having abundant strength for resisting all possible compressions—that is to say, if the forces acting upon a section of flooring supported between two posts be analyzed it will be found that the tendency of the floor-section to sag between its supports will cause the lower layers of the flooring to be under tension while the upper layers of the flooring are under compression, these strains being of course greatest at the top and bottom layers, respectively, and diminishing to zero at the neutral axis near the center of the flooring. In addition to this the weight of a section of flooring causes a shearing strain at its line of contact with its supports.

The principle upon which I have worked in constructing my flooring is to permit concrete alone to resist compressions and to supply a maximum amount of metal at points where the flooring is to be subjected to greatest tensions and shearing strains. In carrying out this principle in some instances—for example, where there are wide spans between adjacent posts—I have employed a greater number of layers of wire-netting near the center of the span than at the ends of the span, the distribution of the metal in any one span following substantially the same rules that would be followed in distributing material in the construction of flat arches, in all cases the distribution of the metallic network in the flooring being carefully calculated and varied according to the columnation of the building, the thickness of the flooring, and the weights

to be sustained. Furthermore, in constructing flooring according to my invention of greater thickness than fifteen inches the center of the flooring may be left hollow, although up to about the thickness of fifteen inches I prefer to construct solid floorings.

Referring to the accompanying drawings by reference characters for a detail description of my invention, A designates the posts or uprights of a building. The posts A may be of ordinary cast-iron construction, although wooden posts may in some cases be employed, and in other instances, also, I contemplate using posts molded out of concrete. Resting on top of the posts A are floor-plates B, and resting upon and supported by the floor-plates B is a flooring comprising a metallic network consisting of strips of wire-netting C, which are laid from post to post and also diagonally between said posts, and concrete D, inclosing the metallic network. The concrete D may be of uniform character, if desired, although in some cases, as illustrated in Fig. 4, the bottom layer D¹ may be of the best quality of concrete, while the center layer D² may be formed by cinder concrete, and the top layer D³ may be a facing of neat Portland cement or best-quality concrete.

The floor-plates B above and below the floor may be bolted together by bolts F, extending through the flooring, the bolts being molded in place when the concrete is poured, and the posts A may, if desired, be bolted to the floor-plates by tapped bolts G.

Laid on top of the concrete D and, if desired, directly supported thereby is an ordinary wooden flooring H.

The staging which is erected to support the flooring while the same is molded and laid in place is of the ordinary construction and need not be herein shown or described. When this staging is removed, however, it is frequently desirable to provide for a further temporary supporting of the flooring until the same becomes so permanently set as to be beyond possibility of injury.

As shown in the third sheet of drawings, to provide temporary supports for a flooring constructed according to my invention after its staging is taken down I preferably use spring-props comprising end pieces or capitals, each consisting of a plank face 10, a rectangular frame 11, and the metallic spring-frame 12. Connecting these end pieces is a pipe 13, having rounded ends, extending from which are pins 14, engaging sockets in the spring-frame. In setting the spring-supports in place the top and bottom pieces are set slightly out of line, the connecting-pipe 13 being of sufficient length, so that when the bottom piece is driven into place beneath the top piece the spring-frames will be slightly compressed to support the flooring.

When flooring of a greater depth than fifteen inches is required or when lightness is absolutely essential, instead of employing a

solid flooring my invention may be embodied in a hollow flooring. A construction for this purpose is illustrated in Fig. 3, in which a hollow flooring is shown, consisting of a bottom section M, tapering upright sections N, and a top concrete section O. In this construction the wire network C is ordinarily employed only in the lower concrete section M; but, if desired, a skeleton framing of network may be employed, so as to reinforce both the top and bottom sections M and N, as well as the top sections O, as illustrated in the attached section of flooring at the left of Fig. 3.

The construction I preferably employ for extra-wide spans between the posts A is illustrated in Fig. 4. As shown in this figure, in addition to the lengths of wire-netting C, which are laid from post to post, short lengths C' of wire-netting are laid near the center of the span between the posts, so that the distribution of metal in a wide span of this character would be similar to the distribution of material adopted in constructing flat arches.

Considering now a completed flooring constructed according to my invention as compared with ordinary wooden floorings, I have provided a fireproof construction which has no sanitary objections and which can be laid by unskilled labor, while compared with the so-called "fireproof" floorings employed in the more expensive types of buildings I have provided a flooring which entirely dispenses with the use of girders, floor-beams, and, in fact, any class of rolled ironwork, while the strength of my flooring I have found by actual tests will compare favorably with any of the more common forms of terra-cotta or combination flooring, and I have actually demonstrated this to be the fact by employing floors constructed according to the invention herein described in buildings where only the highest grades of construction could possibly be employed.

I am aware that numerous changes may be made in practicing my invention by those who are skilled in the art without departing from the scope thereof as expressed in the claims. I do not wish, therefore, to be limited to the constructions I have herein shown and described; but

What I do claim, and desire to secure by Letters Patent of the United States, is—

1. The combination of separated posts or supports, and a flooring consisting of metallic network formed by strips of wire-netting inclosed therein, so as to radiate from the posts or supports on which the floor rests.

2. A flooring resting on separated supports, and consisting of concrete with metallic network so arranged therein that the amount of metal will be greatest at the points where the greatest tensile and shearing strains are to be supported.

3. A flooring resting on separated posts, and consisting of metallic network formed by

strips of wire-netting laid from post to post to cross each other in cob-house fashion, and concrete inclosing the metallic network.

4. A flooring resting on separated posts, 5 and consisting of metallic network formed by strips of wire-netting laid from post to post, and on the diagonals of the figures outlined by the posts, and concrete inclosing the metallic network.

10 5. A flooring resting on separated supports, consisting of concrete having a metallic net-

work inclosed in the bottom layer thereof, with the body portion of said concrete of lighter material than the bottom layer thereof.

In testimony whereof I have hereunto set 15 my hand in the presence of two subscribing witnesses.
